UNITED STATES PATENT OFFICE.

ANTONI ZUBRYD, OF CASTLE SHANNON, PENNSYLVANIA.

BURGLAR-CATCHING DEVICE.

1,217,381.

Specification of Letters Patent. Patented Feb. 27, 1917.

Application filed June 10, 1915. Serial No. 33,410.

To all whom it may concern:

Be it known that I, ANTONI ZUBRYD, a subject of the Emperor of Austria-Hungary, residing at Castle Shannon, in the county of 5 Allegheny and State of Pennsylvania, have invented certain new and useful Improvements in Burglar-Catching Devices, of which the following is a specification.

This invention relates to certain new and 10 useful improvements in burglar catching devices.

The primary object of this invention is to provide automatically operated mechanism positioned adjacent a door whereby any 15 unauthorized person tampering with the securing means of the door is caught and imprisoned until liberated by others.

A further object of the device is to provide an automatic catching device for any 20 person endeavoring to open an outside door thereof when the device is in its set position, an automatically operable tiltable door approach being arranged in connection with a receiving cage and the device having an indicating signal in connection therewith.

A still further object of the invention is to provide an automatic actuating catching trap for burglars arranged adjacent an entrance door and provided with a signal for 30 indicating the presence or absence of an occupant of the trap.

With these general objects in view and others that will appear as the nature of the invention is better understood, the same consists in the novel combination and arrangement of parts hereinafter more fully described, illustrated in the accompanying drawings, and pointed out in the appended claims.

40 In the drawings forming a part of this application and in which like designating characters refer to corresponding parts throughout the several views:—

Figure 1 is an inside front view of a portion of a door provided with the present device, parts of the said device being broken away.

Fig. 2 is a vertical longitudinal sectional view through the door and with the device 50 shown in side elevation and partly broken away.

Fig. 3 is a top plan view of the device with the door actuating means detached, and

Fig. 4 is a perspective view of an upper 55 portion of the device in its set position.

Fig. 5 is a fragmentary sectional view, enlarged, of the lock and pusher, showing the latter abutting the T-head of the lock hub.

Referring more in detail to the drawings, the wall 10 of a housing is herein illustrated 60 provided with a door 11 having a lock 12 interiorly thereof of substantially the usual form and provided with turn knobs 13 for operating the latch thereof not shown. A pit or cellar 14 is arranged beneath the door 65 and extends outwardly thereof, and is provided with a casing 15 rectangular in cross section, vertically mounted therein and constituting a receiving cage. The said casing 15 is provided with a trap door 16 at the top 70 thereof the same being hinged as at 17 to the forward edge of the casing and being provided with a return spring 18 normally retaining the door in its closed horizontal position, the same being immediately in front of 75 the door 11.

Retaining bolts 19 are slidably positioned through oppositely arranged slots 20 in the sides of the casing 15 and are adapted to project inwardly of the said casing for normally supporting the door 16 and allowing persons to freely walk thereover when passing inwardly and outwardly of the doorway. Angular operating levers 21 are pivoted as at 22 to the outer ends of the bolts 19 80 and are pivotally mounted in brackets 23 carried by the opposite sides of the casing 15.

A releasing bar 24 is pivoted in bearings 25 upon the forward side of the casing and is provided with angularly projecting curved arms 26 at its opposite ends. The levers 21 are provided at their outer ends 27 with chains 28 having weights 29 at their free ends and being provided with intermediately arranged hooks 30 adapted for engaging the 95 arms 26 of the bar 24. The hooks 30 engage the same when the said arms are positioned substantially horizontal in set position and at which times an intermediate finger 31 of the bar 24 is seated upon the top of a bracket 100 32 carried by the adjacent side of the casing 15.

An angular trip lever 33 is pivoted as at 34 to the top of the bracket 32 in such a manner that its shorter end 35 has a path of 105 movement in the same plane as the finger 31.

A plate 36 is slidably arranged upon the door wall 10 adjacent the door lock 12 and is so positioned that any turning of the knob 13 will cause the latch actuator to operate 110

a pusher 55 to slide the said plate 36 outwardly and away from the lock 12. The pusher 55 which is carried on the plate 36 projects into the casing of the lock as clearly shown in Figs. 1 and 5. In Fig. 5, a common form of lock is shown, and the hub 56 thereof has the usual cross-arm or T-head 37 against which the free extremity of the pusher 55 abuts. The turning of the hub 56 in either direction rocks the head 37 and forces the pusher 55 outwardly through the casing of the lock 12, sliding the plate 36 in a direction to trip the mechanism.

It will thus be seen that in the present embodiment of the invention the usual form of lock may be employed to actuate the weight-releasing means. The lever 37 is pivoted as at 38 in the side walls of an adjacent floor opening through which the same extends and has its lower end pivotally connected with a link 39, that is pivotally attached as at 40 to the trip lever end 35. The lever 37 has an upper end portion 41 provided with a slot 42 for engaging a pin 43 upon the plate 36, the said portion 41 being adjustably secured to the lever 37 by means of a winged nut 44 whereby the lever may be readily disengaged from the plate 36 when desired to render the device inoperative.

With the elements positioned as best illustrated in Figs. 1 and 4 of the drawings, any manipulation of the knob 13 will result in an outward movement of the plate 36 caused by the latch actuator engaging the slide bar 55, which will pivotally move the lever 37, thereby shifting the trip lever 33 and bringing the shorter arm 35 thereof against the bar finger 31, thus forcing the said finger off of the bracket 32 to allow the weights 29 to revolve the bar 24. Such a turning of the said bar 24, lowers the hooks 26, so that the weights 29 are released and are allowed to fall, which movement operates the lock levers 21 and automatically releases the bolts 19 from beneath the trap door 16. It will thus be seen that a turning of the door knob 13 results in automatically unlocking the trap door 16 upon which the operator is positioned and whereby the said person is precipitated interiorly of the casing 15 which constitutes a receiving cage and makes the burglar a prisoner.

A false bottom 45 is arranged within the casing 15 being suspended from the opposite sides thereof by means of retractile springs 46 for resiliently mounting the bottom 45 above the floor 47 of the casing cage. A guiding post 48 is centrally carried by the false bottom 45 and slidably moves through a central perforation 49 of the casing floor during the operative movements of the device. A signal block 50 is positioned adjacent the door 11 designed to be protected by the device, the said block being mounted upon the false bottom 45 of the cage by

means of a rod 51. The precipitating of a person into the cage 15 through the trap door 16 thereof allows the person to fall upon the resiliently mounted false bottom 45 therein from which he may be liberated by any authorized person through a side door 52 arranged in the said cage. A leaf spring 53 is carried by the cage 15 and is connected to the trip lever 33 by means of a chain 54 whereby the said trip lever is automatically returned to its normal position after the actuation thereof.

It will be understood that the operating means for the tripping mechanism as well as the signal 50 are arranged interiorly of the room as best illustrated in Fig. 2 of the drawings and that either the outside or the inside knob 13 will operate the mechanism although of course only the outside knob would be advantageous for the present object of catching a person endeavoring to enter the house.

The device is thus efficient and serviceable in preventing any unauthorized attempts to open the door 11 and is operable when the connecting portion 41 of the lever 37 is attached to the shiftable blade 36 and when the weighted hooks 30 are mounted upon the horizontally arranged arms 26 with the bolts 19 supporting the trap door 16. It will be seen however that at desired intervals such as during the day time, the upper lever portion 41 may be disengaged from the plate 46 thus rendering the device inoperable although otherwise arranged in its set position, and it will be also seen that the door 16 is automatically returned to its horizontal position by the afore-mentioned spring 18 and that after being tripped, the elements may be readily reset by a person familiar with the structure.

The weights 29 are relatively light, and are sufficient only to retract the latches 19 when the weights are released. As the weights fall through a considerable distance, the momentum thereof increases the effective pull of the weights and is sufficient to retract the latches. Thus, but relatively slight pressure is required for sliding the rod 24 which supports the weights normally, to disengage the projection 31 from the ledge 32.

While the form of the invention herein shown and described is what is believed to be the preferred embodiment thereof, it is nevertheless to be understood that minor changes may be made without departing from the spirit and scope of the invention as claimed.

What I claim as new is:—

1. A device of the class described comprising in combination with a house door, a normally horizontally positioned trap door adjacent the same, shiftable supporting bolts for the trap door, a turn knob for the house

door, and automatic trip releasing means for the said bolts operatively associated with the knob.

2. A device of the class described comprising in combination with a house door, a turn knob for the door, a casing cage positioned forwardly beneath the door, a swinging lid for said cage normally positioned horizontally forwardly of said door, slidable retaining bolts carried by the cage and normally positioned beneath said lid, retracting levers for the bolts, a bar journaled to said cage and having curved projecting ends, chains operatively attached to said levers, 10 weights secured to the free ends of the chains, hooks attached to the intermediate portions of said chains, and normally arranged upon the said bar ends when the device is in its normal set position, and tripping means for the bar operatively associated with said knob.

3. A device of the class described comprising in combination with a house door, a turn knob for the door, a casing cage positioned forwardly beneath said door, a swinging lid for the cage normally positioned horizontally forwardly of the door, slidable retaining bolts carried by the cage and normally positioned beneath the lid, retracting levers 20 for said bolts, a bar journaled on said cage and having curved projecting ends, chains operatively attached to said levers, weights secured to the free ends of the chains, hooks attached to the intermediate portions of the 25 chains and normally arranged upon the bar ends when the device is in its normal set position, a bracket upon said cage, the said bar being longitudinally shiftable and having a finger portion normally flatly positioned 30 upon the top of said bracket, an angular trip pivoted to the upper side of said bracket and having a path of movement in the same plane as the same finger portion, a slide plate operatively associated with said knob; a pivoted operating lever having a shiftable 35 upper end portion detachably and pivotally connected to the said plate, and pivotal link connections between the lower end of said operating lever and said trip lever.

disengageable operative connections between 45 the said trip lever and actuating means.

4. A device of the class described comprising in combination with a house door, a turn knob for the door, a casing cage positioned forwardly beneath said door, a swinging lid 50 for the cage normally positioned horizontally forwardly of the door, slidable retaining bolts carried by the cage and normally positioned beneath said lid, retracting levers for said bolts, a bar journaled on said cage 55 and having curved projecting ends, chains operatively attached to the levers, weights secured to the free ends of the chains, hooks attached to the intermediate portions of the chains and normally arranged upon the bar 60 ends when the device is in its normal set position, a bracket upon said cage, said bar being longitudinally shiftable and having a finger portion normally flatly positioned upon the top of the bracket, an angular trip 65 pivoted to the upper side of said bracket and having a path of movement in the same plane as the same finger portion, a slide plate operatively associated with said knob; a pivoted operating lever having a shiftable 70 upper end portion detachably and pivotally connected to the said plate, and pivotal link connections between the lower end of said operating lever and said trip lever.

5. A device of the class described comprising in combination with an outside door having operating turn knobs, a casing cage positioned beneath and outwardly of said door, a hinged lid for the said cage, a resiliently suspended false bottom within the 80 cage, a signal flag mounted upon the false bottom and positioned adjacent said door, shiftable supporting bolts for said lid, and tripping releasing operating means for said bolts operatively associated with said knobs. 85

In testimony whereof I affix my signature

ANTONI ZUBRYD.
